UNITED STATES PATENT OFFICE.

ALBERT STROBEL, OF CLEVELAND, OHIO.

WINDOW CONSTRUCTION.

Application filed February 28, 1924. Serial No. 695,707.

To all whom it may concern:

Be it known that I, ALBERT STROBEL, a citizen of the United States, residing at Cleveland, in the county of Cuyahoga and 5 State of Ohio, have invented certain new and useful Improvements in Window Constructions, of which the following is a specification.

This invention relates to improvements in 10 window construction having for an object to provide means to insure against entry of rain, snow, etc., through the meeting points of the several parts of a window.

Another object is to provide means for 15 expelling any water which may leak through the joints.

A further object is to provide a window 20 construction which may be completely set up or assembled prior to delivery to the structure being built thereby eliminating considerable expense due to loss of time in the building operation.

It is likewise an object to provide a window 25 sash and jamb construction of the casement or French window type capable of substitution for the usual vertically slideable sashes, at the same time requiring only a slight alteration in the frame construction.

Other objects will be in part obvious and 30 in part pointed out hereinafter.

In order that the invention and its mode 35 of operation may be readily understood by persons skilled in the art, I have in the accompanying illustrative drawings, and in the following detailed description based thereon set out the preferred embodiments of the same.

In these drawings:

Fig. 1 is a vertical transverse sectional 40 view of a casement window sash and jamb designed as a substitute for the usual sliding sash.

Fig. 2 is a horizontal sectional view of a 45 portion of the sash and frame shown in Figure 1.

Similar reference characters indicate similar parts throughout the following specification.

Often-times it is very desirable to substitute swinging sashes or French windows for the usual vertically sliding sashes and through the construction about to be set forth this can be readily accomplished without rendering the window frame unsightly.

As shown in Figures 1 and 2, this con-

struction consists in the formation of an independent frame 26 which is arranged in the main frame after removal of the usual parting strips. The vertical stiles or jambs 27 are arranged to fit in and entirely fill the 60 space usually occupied by the upper sash, these stiles extending from the lower rail or window jamb 28 to the upper rail 29. The inner faces of the stiles 27 are channeled for the reception of tongues 30 carried by 65 the sashes whereby to form tight joints when the sashes are closed. In order to provide a water tight joint at the top, the rail 29 is formed with a depending rib or flange 31 which engages over a portion of the outer 70 face of the upper rail. The jamb or sub sill 28 has its lower face beveled to conform to the inclination of the sill S and is cut to form steps 32 upon its upper side whereby 75 to limit the outward movement of the sashes and to provide an irregular joint which will resist the passage of water or the like therethrough. As shown, the lower rail of the sash 33 is stepped to snugly engage the steps on the sub sill 28 and in addition carries 80 a water nose 34 upon its outer face, this water nose being extended beyond the vertical plane of the outer face of the sub sill and having tongue and groove connection with the sash rail. This water nose 34 is substantially triangular in cross section and has its under face longitudinally channeled as 85 at 35 to prevent passage of water to the stepped joint.

In order that the frame 26 may be securely held in position, and at the same time present a neat and finished appearance, I provide a set of finishing strips or panels 36 of such width as to cover the space between 90 the frame 26 and the finish casing F.

The upper and lower panels as indicated 95 are plain while the side panels are each provided with a rib or tongue 37 which snugly fits in the groove formerly occupied by the usual parting strip. These vertical or side panels as shown, abut the inner faces of the independent frame 26 and thereby prevent its being accidentally displaced. As is obvious the frame 26 and the panels 36 together 100 cover the inner faces of the main frame and sill, consequently covering the usual pulley openings and any unsightly portions.

In this construction provision is made for 105 the drainage of any water that may leak through the joints, this provision being the 110

formation of the outlet opening 38 in the sub-sill 28 and preferably though not necessarily lining it with a pipe 39 as shown.

It is obvious that this is a highly desirable construction in that the independent frames may be entirely completed and then transported to the building ready for mounting in the old frame. The parting strips and the window stops are first removed and the sliding sashes taken out, after which the independent frame 26 is arranged in position and the panels 36 are attached to the main frame. This completes the operation and I now have a desirable weather proof casement 15 or French window.

Manifestly, the construction shown is capable of considerable modification and such modification as may fall within the scope of my claims, I consider within the spirit of 20 my invention.

I claim:

1. The combination with a window frame having vertical inner and outer sash guide

ways, and substantially centrally arranged parting strip grooves between the guide 25 ways; of a supplemental frame arrangeable in the outer guide way, panels covering the inner guide way, and ribs integrally formed with the panels to fit in said parting strip grooves whereby to retain the supplemental 30 frame in position.

2. The combination with a window frame having vertical inner and outer sash guide ways, and substantially centrally arranged parting strip grooves between the guide 35 ways; of a supplemental frame arrangeable in the outer guide way, panels covering the inner guide way, ribs integrally formed with the panels to fit in said parting strip grooves whereby to retain the supplemental frame in 40 position, horizontally swinging sashes hinged to the supplemental frame, and a stepped joint between the lower bars of the sashes and the supplemental frame.

In testimony whereof, I affix my signature.

ALBERT STROBEL.
